(57) **CLAIM**

The ornamental design for an LED downlight retrofit luminaire with double leaf spring mounting mechanism and rotating friction blades to accommodate housings, as shown and described.

DESCRIPTION

FIG. 1 is a top perspective view of the LED downlight retrofit luminaire with double leaf spring mounting mechanism and rotating friction blades to accommodate housings, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a bottom perspective view thereof; and,

FIG. 9 is an exploded view thereof.
